UNITED STATES PATENT OFFICE

GEORGES GRANDJEAN, OF LES FORGETS, ISLE ADAM, FRANCE, ASSIGNOR TO ISOTHERMOS CORPORATION OF AMERICA, OF NEW YORK, N. Y., A CORPORATION OF DELAWARE

JOURNAL BOX

Application filed January 22, 1929, Serial No. 334,141, and in Switzerland November 14, 1928.

In automatically lubricating journal boxes of the type having an oil reservoir in the bottom thereof from which the oil is conveyed by suitable means to the parts to be lubricated, such as the bearing and journal within the box, trouble is experienced by reason of the escape of oil through the openings in the walls of the box and particularly through the opening through which the shaft 10 extends, which opening is usually closed against the entrance of dust into the box by means of a dust guard. Such trouble usually results from the fact that the boxes are provided with too much oil, bringing it above its normal level and thereby causing the distribution of a surplus quantity of the oil with a consequent loss of same. Furthermore, it has been found that the over supply of oil in the box is sometimes so great as to 20 bring it into contact with the dust guard, with the result that the latter, which is usually formed of felt or other absorbent material, soon becomes ineffective in the performance of its function.

Because of the troubles referred to, as well as others not herein specifically mentioned, incident to the filling of the oil reservoir above its normal height, it has been the object of the present invention to provide means for limiting the height of the oil in the reservoir to that assuring the best operation of the box. To this end, the invention, in its preferred form, comprises the provision of an overflow opening in the wall of the reservoir positioned to establish the desired height of the oil therein, a filling opening at a level above the overflow opening, and closures for said openings, the closure for the overflow opening being so connected with the closure 30 for the filling opening as to necessitate its removal either simultaneously with or prior to the removal of the filling opening closure. In this way, filling of the reservoir above its normal height as established by the overflow opening will be prevented.

The accompanying drawings show, by way of example, different embodiments of the invention.

Fig. 1 is a front end elevation of a journal box equipped with the invention.

Fig. 2 is a vertical longitudinal section of the box, on the line 2-2 of Fig. 1, shown in association with the journal end of an axle having an oil distributor applied thereto.

Fig. 3 is a side view of the front end of the box.

Fig. 4 is a partial front end view of the box showing the overflow opening arranged at one side thereof.

Fig. 5 is an enlarged sectional detail showing the connection between the closures of the filling and overflow openings.

The box here shown, aside from the features of the present invention, is substantially the same as that disclosed in the Eveno Patent No. 1,617,205, to which reference may be had. It comprises the box proper, indicated at 1, which is provided at its bottom with an oil well or reservoir 4. Mounted in a suitable seat in the top portion of the box is a bearing 3 having an extension 3' overhanging the end of the axle, which latter is provided with the usual journal 5 engaging the bearing 3. Secured to the end of the axle for rotation therewith is the oil elevating device or paddle 2 having terminal sections 9, which during rotation of the axle, pass through the oil in the reservoir and pick up a film or coating of oil, which, when the ends of the paddle pass through the upper arc of their rotation, is discharged therefrom for distribution onto the bearing, which latter is provided with the usual oil distributing ducts and channels for leading the lubricant to the engaging faces of the journal and bearing. The box, at its inner end, is provided with the usual dust guard 6 in contact with the axle for preventing entrance of dust or like foreign matter into the box at such end.

The box at its front end is provided with the usual opening 10 for giving access to the box for any desired purpose including that of filling the oil reservoir. It will therefore be referred to herein as the filling opening.

This opening is normally closed by a cover or closure 14 which is held in position on the box by suitable fastening means, such as the screws 7.

In filling the reservoir through this opening 10 there is a tendency on the part of the trainman or other person having the work in

hand to pour in an excess quantity of oil and thereby bring it up above the normal level adapted for the best functioning of the parts, as hereinbefore referred to. To avoid this I 5 provide the box with an overflow opening 11 positioned to establish the desired height of the oil, as indicated at 12, which opening is normally closed by a suitable closure, here shown in the form of a screw plug 13 having 10 a head 14 and an intermediate spacing portion 15 of slightly greater diameter than the plug providing a shoulder 16 for engagement with a washer 17 serving as a seal to more effectively close the overflow against leakage of 15 the oil.

If this closure for the overflow opening is removed each time oil is supplied to the reservoir through the filling opening, it would effectively serve its purpose of limiting the oil 20 to its proper height, but it has been found in practice that it is not so removed; therefore, in accordance with the present invention, I have connected this closure 13 with the filling opening closure 14 in such manner as to render 25 it necessary to remove the closure 13 preliminary to the removal of the closure 14. In this way positively insuring against the filling of the reservoir above the proper predetermined level. Such connection of the closures 30 may be effected in any suitable or desired way. In the present case, the closure 14 is formed with an annular extension 18 overlying the upper surface of the wall containing the overflow opening and having an opening or perforation 19 through which the closure 13 extends with its head 14 overlying said extension as shown. With such connection of the parts, it will be clear that the closure 14 cannot be removed without first removing the 35 closure 13.

It will be noted that extension 18 of the closure 14 is spaced from both the underlying wall of the box and from the head 14 of the closure 13 and also that the perforation 40 19 of the extension is of substantially greater diameter than the part 15 of said closure 13; this spacing of the closures enabling each to be adjusted to their respective seats independently of each other. It will also be noted 45 that the connection of the overflow closure 13 with the closure 14 is such as to permit it to be removed from and replaced in the overflow opening independently of the filling opening closure 14.

50 To prevent the introduction of oil or other lubricant into the box by only partially opening the cover 14 and permitting the plug 13 to remain in place, means are preferably provided for preventing any such partial opening 55 of the cover 14 without the prior complete removal of the plug. Any suitable means may be provided for such purpose, the means here shown comprising a lug 22 on the box 60 which is arranged to overhang the front side 65 of the cover adjacent its upper edge whereby

it will be necessary to swing the lower edge of the cover outwardly from the box to release it from said lug and to do which it obviously will be necessary to first completely remove the plug 13.

As shown in Figs. 1 to 4, the overflow opening is arranged at the front end of the box. This however is only exemplary, such opening may be at one side of the box, as shown in Fig. 5, or any other desired location or arrangement of either or both of the openings may be had without departure from the invention.

While the opening 11 has been herein referred to as the "overflow" opening, it will of course be understood that it may be also used as a filling opening and, as a matter of fact, is ordinarily so used.

What I claim is:

1. A journal box having an access and filling opening and a reservoir below the same, and also having an overflow opening positioned below said access opening to establish a desired height of oil in the reservoir, a cover for the access opening, and a closure member for the overflow opening, said closure member also constituting means for preventing the removal of the cover prior to the removal of the closure member.

2. A journal box having an access and oil filling opening and a reservoir below the same, and also having an overflow opening positioned below said access opening to establish a desired height of oil in the reservoir, a lug on the box at one side of the access opening, a cover for said access opening fitting under said lug, and a closure member for said overflow opening located in obstructing relation to the edge of the cover opposite the lug whereby the cover must be closed before the closure member is fitted in the overflow opening.

3. A journal box having a combined access and oil filling opening, and also having a reservoir and an overflow opening, a cover for the access and filling opening having a portion arranged adjacent the overflow opening, a closure member for the overflow opening and means on the outside of the box adjacent the combined access and filling opening whereby the cover must be seated prior to the fitting of the closure member in the overflow opening.

4. A journal box having an oil reservoir, an overflow opening, a filling opening above the overflow opening, a closure for the filling opening having a perforated extension, a closure for the overflow opening extending through the perforation of said extension and having a head overlying the latter, for the purpose specified.

5. A journal box having an oil reservoir, an overflow opening, a filling opening above the overflow opening, a closure for the filling opening having a perforated extension oppo-

site the overflow opening, a closure for the latter extending through the perforation of said extension and having a head overlying the latter, for the purpose specified.

6. A journal box having an oil reservoir, an overflow opening, a filling opening above the overflow opening, a closure for the filling opening having a perforated extension, and a closure for the overflow opening extending through the perforation of said extension and having a head overlying the latter, the said extension being spaced from both the overflow closure and the wall of the box containing the overflow opening, for the purpose specified.

15 7. A journal box having an oil reservoir, an overflow opening, a filling opening above the overflow opening, a closure for the filling opening having a perforated extension overlying and spaced from the wall containing the overflow opening, and a closure for the overflow opening in the form of a threaded plug having a portion extending through the perforation of the extension of less diameter than said perforation and also having a head overlying the extension and spaced therefrom, for the purpose specified.

8. A journal box having an oil reservoir, an overflow opening positioned to establish a desired height of oil in the reservoir, a filling opening above the overflow opening, closures for said openings, and means including the overflow closure for engaging the filler opening closure and preventing removal of the latter prior to the removal of the overflow closure.

40 9. A journal box having an oil reservoir, an overflow opening positioned to establish a desired height of oil in the reservoir, a filling opening above the overflow opening, closures for said openings, and means including the overflow closure and a lug on the box for engaging the filler opening closure at different points thereof for preventing removal of the latter prior to the removal of the overflow closure.

45 In testimony whereof I affix my signature.
GEORGES GRANDJEAN.
